UNITED STATES PATENT OFFICE.

PERRY L. TENNEY, OF ALAMEDA, CALIFORNIA.

ADJUSTABLE DROP-LIGHT BRACKET.

No. 931,162.

Specification of Letters Patent.

Patented Aug. 17, 1909.

Application filed October 31, 1908. Serial No. 460,454.

To all whom it may concern:

Be it known that I, PERRY L. TENNEY, a citizen of the United States, residing at Alameda, in the county of Alameda and State 5 of California, have invented certain new and useful Improvements in Adjustable Drop-Light Brackets, of which the following is a specification.

This invention relates to lighting fixtures 10 and refers especially to a device for supporting an electric light.

An object of this invention is to construct a bracket to be applied to the cord of a depending electric light by means of which the 15 light may be adjusted to various positions and angles.

Another object of this invention is to construct a bracket of this nature which is of simple construction, easy of operation and is 20 strong, durable and of economical manufacture.

Other objects and advantages will be apparent from the following description and it will be understood that changes in the specific structure shown and described may be 25 made within the scope of the claims without departing from the spirit of the invention.

In the drawings forming a portion of this specification, and in which like numerals of 30 reference indicate similar parts in the several views, Figure 1 is a side elevation of an electric bulb having the improved bracket applied thereto, Fig. 2 is a side elevation of the bracket detached, Fig. 3 is an edge view 35 of the bracket arm detached from the clamping ring, Fig. 4 is a detailed edge view of the clamping ring, Fig. 5 is an opposite edge view of the clamping ring.

Referring to the drawings 10 designates 40 an electric bulb which is supported in the socket 11 and which is provided with a shade 12. The socket 11 is supported upon a drop wire 13 which also conducts the current to the bulb 10.

The improved bracket comprises a metallic 45 split ring 14 formed from wire which is provided with loops 15 and 16 upon the opposite ends thereof. The loop 15 comprises a turned-over portion of wire which is flattened upon its inner face and which is provided 50 with a threaded central portion for the engagement of the threaded thumb screw 17. The loop 16 is formed by turning over a portion of the wire and flattening the same 55 upon both sides. The outer flattened surface

of the loop 16 is provided with a number of serrations as shown in the drawings at 18. The loop 16 is formed of a greater size than the loop 15 for the purpose of obtaining a large serrated surface. 60

The ring 14 is supported upon the lower extremity of an arm 19 which is formed of wire and which is flattened and serrated as at 20 at its lower end to engage against the serrated surface 18 of the ring 14. The 65 portion 20 is apertured to receive the thumb screw 17 to bind the portion 20 to the surface 18 to secure the ring 14 in adjusted position. The upper end of the arm 19 is formed substantially S-shaped as at 21 for the reception 70 of a portion of the drop wire 13 which is frictionally engaged therethrough.

In operating the device the S-shaped portion is engaged with the wire 13 and the socket 11 is secured through the ring 14 and 75 held in such position by the thumb screw 17 which is passed through the flattened portion 20 of the arm 19 and into the loops 16 and 15 respectively where it is tightened and so held by reason of its threaded engagement 80 with the loops 15. The bulb 10 can be secured at any desired angle by releasing the thumb screw 17 and swinging the ring 14 about the thumb screw 17 as a pivot point to the position required when the serrated 85 faces 18 and 20 are clamped together by the thumb screw 17.

What I claim is:—

1. In a bracket the combination of an arm, an S-shaped friction wire-engaging member 90 on said arm, a flattened and serrated portion on the opposite extremity of said arm, a ring having loops formed thereon, said loops being flattened and having one face thereof serrated for engagement against the serrated 95 portion of said arm and a thumb screw disposed through said arm and said loops for securely holding said ring in adjusted position.

2. In a device of the class described, the 100 combination of an arm, an S-shaped wire-engaging member disposed upon the upper extremity of said arm, a flattened and serrated portion formed upon the lower extremity of said arm, a ring having loops formed 105 at the opposite extremities thereof for engagement about an electric bulb socket, a flattened and serrated face disposed upon one of the loops of said ring for engagement with said flattened and serrated extremity, 110

there being a threaded portion formed centrally of the opposite of said loops and a thumb screw disposed through said loops and said flattened and serrated portion on said 5 arm and engaging said threaded portion for securing said ring about a bulb socket and to hold the same in various angles.

In testimony whereof I affix my signature, in presence of two witnesses.

PERRY L. TENNEY.
